US0D1109727S

(12) **United States Design Patent** (10) Patent No.: **US D1,109,727 S**
(45) Date of Patent: ** Jan. 20, 2026

(54) **WIRELESS EARPHONE CHARGING CASE**

(71) Applicant: **Shenzhen City Flyco Flute System Development Co., Ltd.**, Guangdong (CN)

(72) Inventors: **Jiugao Peng**, Guangdong (CN); **Ruiwen Shi**, Guangdong (CN); **Guixiao He**, Guangdong (CN); **Shiwen Guo**, Guangdong (CN); **Lei Cao**, Guangdong (CN); **Fuhua He**, Guangdong (CN); **Haiquan Wu**, Guangdong (CN)

(73) Assignee: **Shenzhen City Flyco Flute System Development Co., Ltd.**, Shenzhen (CN)

(**) Term: **15 Years**

(21) Appl. No.: **29/824,789**

(22) Filed: **Jan. 27, 2022**

(30) **Foreign Application Priority Data**

Nov. 1, 2021 (CN) 202130715402.0

(51) LOC (15) Cl. **13-02**

(52) U.S. Cl.

(57) **CLAIM**

The ornamental design for a wireless earphone charging case, as shown and described.

DESCRIPTION

FIG. 1 is a top, front and right side perspective view of a wireless earphone charging case, showing our new design; FIG. 2 is a bottom, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines are included to show features that form no part of the claimed design.

1 Claim, 8 Drawing Sheets
